TRACHEA CONNECTION

Ottie Roberts, East St. Louis, Ill.

Application March 22, 1945, Serial No. 584,190

3 Claims. (Cl. 3—1.1)

1

This invention relates to trachea connections, and more particularly to improvements in devices for this purpose which operate to effect a suitable air supply connection between a tracheal opening and the sound box of an artificial larynx or the like.

Since the first appearance of the various types and designs of artificial larynges which have been available for a number of years to those requiring such instruments, considerable difficulty has been experienced in effecting a practical and comfortable connection between a trachea opening and the tube for supplying air therefrom, to an artificial voice apparatus. The present invention has resulted from a number of years of experience of this applicant, as a user, designer and manufacturer of equipment of this general type. The general betterment of and increase of comfort to the user of such devices, constitute general objectives of the present invention.

Due to the fact of surgical removal of the larynx, or because of severe impairment of the vocal chords in any manner necessitating the use of artificial speech devices, it is usually necessary to terminate the trachea or windpipe in an outside orifice surgically formed in the lower frontal portion of the neck. It is to the purpose of providing a suitable, practical, air-tight and comfortable connection from such tracheal orifice to an artificial larynx, that the current improvements are directed.

It is frequently the case that a tracheal opening resulting from the causes noted, is not of truly circular shaping; frequently also they vary in size, and the neck contour of the patient or user of the device may vary considerably so as to necessitate, for best results, a high degree of physical adaptability of the air tube connection to the varying contours and shaping of neck, and the varying nature of tracheal incisions in different individuals. This greater adaptability is obtained as an objective of the present improvements.

More particularly stated in reference to currently novel structure, the invention has as an objective, to provide an easily conforming annular cushion in combination with a cup-like trachea connection, and the attainment of a structure such that the resilient or cushion element of the device may be renewed from time to time without special skill, tools or equipment.

Yet another object of the invention is attained in a tracheal connection such that the bell or cup thereof may be readily adapted, without any

2

special equipment, to surround comfortably certain irregularly shaped tracheal incisions and may thus be readily individualized or personalized to the user.

5 The foregoing and numerous other objects will more clearly appear as the description proceeds.

In the drawing:

Fig. 1 is a side elevation of a trachea connection embodying the present improvements;

10 Fig. 2 is a sectional view along a longitudinal median plane, particularly as taken along line 2—2 of Fig. 1, and illustrating the internal arrangement of parts in assembly, and

15 Fig. 3 is an exploded view of the bell and the sleeve used to effect a tube connection, shown in section, together with a resilient annulus used as a cushioning element, and threaded assembly means.

20 Referring now by characters of reference to the drawing, an air supply tube 10 which may conveniently consist of a suitable high grade rubber or rubber-like material, serves in now well known manner, to direct the air supplied from the trachea opening, to the interior of a sound box or the like, of an artificial larynx, for example of a type such as shown in my copending application of Serial No. 584,189, filed March 22, 1945, and entitled "Improvements in artificial larynx construction." As will best appear from Fig. 2, a suitably tight and readily effected air supply connection consists of an integrally extended sleeve 11, being part of a cup-like or bell-shape body generally indicated at 12. The connecting tube or sleeve 11 is provided with an internal bore 13 of substantial size, which is continued into a bore 14 of even diameter with the bore 13. Beyond this, proceeding toward the air supply or connection end of the device, it will best appear from Fig. 3 that the bore 14 is somewhat enlarged and is internally threaded as at 15 for a purpose hereinafter better appearing.

25 Beyond the threaded bore 15 is the cup or bell structure which may consist of a molded thermoplastic element, including preferably in a single piece, the parts 11 and 12, this unit being molded or otherwise formed so that the chamber 16 within the bell is contoured to approximate closely the frustum of a sphere approaching hemispherical proportions, thus resulting in a relatively deeply cupped fitting.

30 It will now appear that, with a normally circular trachea opening, the device including merely a suitable tube connection and a bell portion such as 12, may be operatively employed of itself,

without other provisions, to complete the communication between trachea and artificial larynx.

It is preferred to form the structures 11-12 of some suitable thermoplastic material, preferably hard rubber of the grade usually sold as rod stock, and which in order to adapt the shaping of bell or cup 12 to meet any unusual individual requirements, may be softened in warm water, reshaped as needed, and upon recooling, will retain the desired oval, oblong or other non-circular shape resulting from the softening treatment.

It is greatly preferred to employ in conjunction with the structure 11-12, a cushioning and air sealing device which, in a thoroughly practical and extremely comfortable form, consists of a deep washer-like element originally in the form of element 17 (Fig. 3). This is cut or molded as an annulus having an initial axial opening 18 of approximately the diameter of the enlarged threaded bore 15, and further provided with rounded margins such as indicated at 20. The initial outer diameter of the annulus 17 is by preference, appreciably greater than the largest diameter of the frusto-spherical bell or cup 16, for a reason hereinafter better appearing.

As a preferred means for assembling the annulus 17 to the body 12, there has been selected and repeated usage made of a tubular screw 21. The bore of screw 21 is preferably, in assembly, 30 a continuation of the bore 14 in element 12, as will best appear from Fig. 2. The diameter of screw 21 is preferably about the same as, or slightly exceeds the diameter of the opening 18, and the threads 21 conform to the female threaded portion 15 of the bell 12. In conjunction with the tubular screw 21 there is preferably employed a thin metal washer 22 formed of a corrosion-resistant metal or material, or alternately surface treated as by plating or dipping, for this purpose.

The assembly of parts will now have become obvious from the foregoing complete description of the several elements. The washer 22 is inserted over screw 21 and brought to abut the inside or under surface of the head 23 of the screw. The screw 21 is then extended through the opening 18 of the annulus 17, and is threaded into the tapped socket or bore 15 as firmly as conditions will permit.

The washer 17 is by preference of a profusely internally cellular construction, and of rubber or a rubber-like material, being characterized by a very marked depthwise resilience and substantial stretch. Now as screw 21 is threaded up, the shape of the internal surface of the bell or cup 16 will result in drawing the central areas of the annulus depthwise into the cup, so that there results, for example, a soft yet substantially complete cushioning liner within the bell, but more importantly, due to the initial diameter of the annulus and its stretching characteristic, there remains extending axially of the mouth of the rigid bell 12, an extremely deep peripheral cushion for the element 12. The resulting structure, upon application to the neck of the user, will according to pressure of application, be at times deflected outwardly to an even larger diameter as may be desired, but upon merely a gentle pressure toward the neck of the user about the tra-

cheal opening, it is now seen that there is provided an element of high depthwise or axial resilience making for extreme comfort.

It is greatly preferred by this applicant not to anchor or secure the trachea connection in any way to the neck, as is sometimes advocated by designers of older forms of trachea connector. It will be observed that with the present device, the connector may be readily applied and removed without effort, and yet with the result of providing a perfectly conforming, readily adapting, substantially air-tight seal over the varyingly irregular neck areas about the tracheal opening.

It will now have appeared that the device as described fully attains the several objectives resulting in the present development, and that in all other ways it will meet the existing demand for a more comfortable and more practical connection of this type.

The detail of description, referring as it does for instruction purposes to a single selected embodiment, is not to be understood in a restricting sense because of the many variants possible within the scope of the appended claims.

I claim as my invention:

1. A trachea connection for use with an artificial larynx instrument or the like, for the purpose of establishing communication from a tracheal opening to an air supply tube to the instrument, the connection including a hollow body internally formed substantially of the contour of a frustum of a sphere, an annulus of cushioning material projecting outwardly of the inlet end of the connection to serve as a neck cushion about the tracheal opening of the user, and securing means gripping the inner margin of the annulus, and attached to an inner central area of the hollow enlargement.

2. In a trachea connector, a trachea cup characterized by a deep internal chamber, a cushioning element consisting of an annulus of cellular rubber-like material, of at least the diameter of the peripheral portion of the cup, and anchored to substantially the deepest end of the cup, the cushioning annulus projecting axially and toward the neck of the user substantially beyond the margin of the cup.

3. A trachea connector consisting of a hard rubber fitting having a deeply cupped enlargement chambered to provide a bell-like structure arranged to be presented toward the tracheal opening, and of a diameter to surround said opening, an annulus of a cellular highly compressible rubber-like material of a diameter exceeding the largest diameter of the cupped enlargement, a tubular screw, a washer fitted over the screw behind the head thereof, the screw extended through the opening of the annulus and having a threaded connection inwardly of the bell structure beyond the deepest portion of the cup, the annulus being of a size such that when the screw is threaded up, the annulus constitutes a deformed liner within the cup-like portion, and extends axially a substantial distance beyond the outer margin of such portion to constitute a cushioning and sealing element peripherally of the cupped enlargement.

OTTIE ROBERTS.
